(57) **CLAIM**

The ornamental design for the light emitting diode, as shown and described.

DESCRIPTION

FIG. 1 is a perspective view of the light emitting diode in a first embodiment;

FIG. 2 is a front view thereof, a rear view being mirror image thereof;

FIG. 3 is a right side view thereof, a left side view being mirror image thereof;

FIG. 4 is a top plan view thereof; and,

FIG. 5 is a bottom view thereof.

The portions of the article in broken lines are shown for illustrative purposes only and form no part of the claimed design.
